UNITED STATES PATENT OFFICE.

JOSEPH C. COULOMBE, OF LOWELL, MASSACHUSETTS.

FUEL-FEEDING AND SUCTION-INDUCING DEVICE.

1,424,715.

Specification of Letters Patent. Patented Aug. 1, 1922.

Application filed March 31, 1917. Serial No. 159,045.

To all whom it may concern:

Be it known that I, JOSEPH C. COULOMBE, a citizen of the United States, and a resident of Lowell, in the county of Middlesex and 5 State of Massachusetts, have invented certain new and useful Improvements in Fuel-Feeding and Suction-Inducing Devices, of which the following is a full, clear, and exact description, whereby any one skilled in 10 the art may make and use the same.

The invention relates to the class of devices which are employed for raising fuel from a source of supply, and distributing the same to the carbureter of an engine or 15 like device. It permits the arrangement of the source at a lower level than the carbureter in which it is used and insures a constant and adequate supply of fuel for the carbureter at all times. A device of 20 the class referred to is illustrated in my co-pending application, Serial No. 159,044, filed March 31, 1917. The invention herein-after described defines matter not claimed in said prior application.

25 It also relates to a means for securing a reduced atmospheric pressure for raising the fuel by utilizing the suction effects of an engine, or a suction effect produced in conjunction with the circulation of the lubricating oil, or both.

It is a principal object of the invention to provide for a proper suction effect under all running conditions of the engine which induces the suction or sub-atmospheric 35 condition for raising fuel to the device.

A further object is to provide a compact, simple form of device having a valve control delicate in its adjustments and positive in its operation.

40 A further object is to provide for accessibility wherein the operating mechanism may be removed as a unit from the main casing for inspection and adjustment.

A still further object is to provide, 45 through the suction inducing apparatus, a positive indication as to the operation of the oil circulating system of the engine.

Referring to the drawings:

Fig. 1 illustrates the various connections 50 for the fuel feed device in conjunction with a gas engine.

Fig. 2 is a view, on enlarged scale, illustrating the connections of the various parts from the source of supply to the delivery point.

55

Fig. 3 is a vertical sectional view through the casing and appurtenant parts, on an enlarged scale as compared with Figs. 1 and 2.

Fig. 4 illustrates a suction connection with the carbureter of the engine, with parts 60 broken away.

Fig. 5 is a sectional view through the pump of the oil circulating system and appurtenant parts.

Fig. 6 is a view similar to Fig. 3 illustrating an arrangement for controlling the fuel inlet.

The invention is illustrated in conjunction with an automobile engine, such a device providing a good example of a wide 70 range of suction effects.

Fuel feeding devices actuated by suction of an engine are not new in the art, but difficulty has been experienced in providing a suction system which would operate with 75 certainty under all of the variable conditions which are inherent in a variable speed engine.

When the throttle of such an engine is nearly closed, there is, ordinarily, excessive 80 suction in the vacuum feed. When the throttle is wide open, there is a diminution of suction to a point which is hardly sufficient to raise fuel to the feed device in sufficient quantity to supply the engine. The 85 apparatus, hereinafter defined, obviates these difficulties by giving a more even suction at all times. It also serves as an indicator for insuring proper attention to the lubricating system.

90

In the accompanying drawings, A, indicates an engine having a manifold 1, connected with the carbureter 2, which carbureter receives its supply of fuel from the vacuum feed tank 3. This tank 3, may be 95 placed in any desired position. Fig. 1 shows it on the engine.

The tank 3, has a suction connection 4, with the intake side of the engine, and is also provided with a suction connection 5, 100 which runs to the oil circulating system of the engine.

The suction connection 4, terminates adjacent to the throttle of the carburetor. One form of construction of the connection is illustrated in Fig. 4, where a boss 6, receives the suction connection 4. The opening 5, of the boss 6, has an expanded opening. One leg 7, of this is at one side of the throttle valve 8. The other leg 9, is at the opposite side. Thus the opening 5, communicates with opposite sides of a closed throttle.

This arrangement provides for equalization of the suction. In the case of a wide open throttle, both legs 7, and 9, of the suction connection are subjected to substantially the same suction. Inasmuch as the openings are located adjacent to the throttle where the greatest restriction to the passage of gas occurs, the suction at this point is considerably greater than it would be if made above the throttle or to some other point of the manifold of the engine.

When the throttle is closed or nearly so, the connection eliminates the excessively high suction. The opening of the leg 9, neutralizes what would ordinarily be a very high suction at the leg 7, provided 7, were the only connection. While there is sufficient suction produced and made effective, this will not become excessively high, due to the by-pass effect of the connected openings 7, and 9, from one side to the other of the closed throttle.

One of the main purposes of the invention is to provide a suction effect for the tank 3, during circulation of oil in the lubricating system.

The lubricating tank is illustrated at 10, and distributes its oil to the engine in any well known manner. No attempt has been made to show the connections from the tank to the various bearings of the engine to be lubricated, it being deemed sufficient to indicate the tank and a connection from the pump to the tank and from the tank to the engine. The oil pump is indicated at 11, and, for convenience of illustration, this is shown as of the rotary type which may be driven from the cam shaft of the engine or in any other suitable manner. The form of pump is quite immaterial.

The function of such a pump is well understood in the art, and is commonly used for circulating the lubricating oil which is required for the engine.

As the lubricating oil is circulated for the engine, it is passed through a device which operates on the principle of an injector. Such a device is illustrated in Fig. 5, and consists of a suitable casing or fitting 12, having a converging nozzle 13, and a diverging nozzle 14. There is a chamber 15, between said nozzles. This chamber, through the pipe or connection 5, produces a suction or vacuum effect in the suction

chamber of the tank 3, as the lubricating oil is forced through the nozzles.

It is apparent that, by using the suction effect produced by a connection with the oil pump and its circulating system, an indication is always given of any lack or improper circulation of oil. If no oil is being fed by the pump, the suction obviously diminishes or stops entirely, and the suction chamber of the tank 3 will not be reduced to sub-atmospheric pressure. As a result, no fuel will be drawn into the suction chamber of the tank, and the engine will "stall" for lack of fuel.

It is impossible to run the engine without proper lubrication without liability of overheating and destroying the engine. The importance of the indication given is apparent, particularly as the circulating system, while the engine is in operation, provides a very certain and advantageous method of producing the required sub-atmospheric condition in the suction chamber of the tank.

By a suitable arrangement of valves and checks in the suction lines 4, and 5, either suction line may be utilized or both may be employed in combination.

The tank 3, is illustrated in Fig. 3 of the drawings. It comprises a main outer casing 16, of cylindrical form which encloses a similar cylindrical casing 17. The casing 17, has, at its lower end, an annular ring 18, to which is secured a plate 19. This plate is removable and gives access to the suction chamber 20, of the casing 17. It also divides and separates said chamber 20, which is the operating and suction chamber of the device, from the distributing chamber 21, of the outer casing member 16.

The chamber 21, has suitable connections 22, which, through a pipe line 22^a, extend to the fuel chamber 2^a, of the carburetor. It distributes its fuel under gravitational action.

The two casings 16, and 17, are bound together and supported by straps 22^b, 22^c. The upper strap 22^b, rests just under the bead 23, of the casing 16, and this bead is engaged by a flange or bead 24, provided at the upper edge of the casing 17. A compression of the upper clamping strap 22^b, binds the two casings together, though there is not a perfect seal effected between the two casings. This lack of seal, when the outer casing is slightly crimped, permits air to enter the chamber 21, and maintain what is substantially an atmospheric pressure therein.

The upper casing 17, contains the operating mechanism, and has, upon its upper end, a connecting block 25, provided with a fuel connection 26, and a suction connection 27, the latter being connected through an opening 28, with the interior of the suction chamber 20.

A screw plug 29, extends across the opening of the fuel connection 26, and has an annular groove 30, and passages 31, 32, connecting the fuel inlet 26, with the fuel inlet tube 33.

The inlet tube 33, forms a supporting guide for an inverted cup 34. This cup 34, is of cylindrical form, and has a downwardly extending tubular bearing 35, encircling the inlet tube 33.

The cup 34, encloses what might well be termed a "liquid seal" chamber 36.

Extending within the chamber 36, there is a float 37, having a guide tube 38, encircling the tube 35. The float 37, is preferably made in sections 39, 40. Clamped between them, is a baffle-cup 41, which prevents air bubbles entering the lower edge of the liquid seal chamber 36, when the fuel level of the chamber 20, lowers.

Secured to the bottom of the float 37, is a bracket 42, preferably of U-form, having a pin and slot connection 43, 44, with a pivoted valve lever 45, which is pivoted to a support 46, mounted upon the partitioning plate 19.

The end of the lever 45, is pivoted as at 47, to a valve rod 48, which controls a valve 49.

The valve 49, has a valve seat 50, formed about a valve opening 51, extending through the partitioning plate 19. This valve 49, and valve opening 51, have a comparatively large area in order to permit a quick emptying of fuel from the suction chamber 20, to the distributing chamber 21.

In order to provide for easy release of said valve 49, from its seat, a relief opening 52, is formed therein and is controlled by a tapered plug 53, which is adjustably secured to the valve rod 48, and passes through a guide bracket 54.

It will be observed that there is but one connection which must be controlled by the float and liquid seal chamber, namely: the valve opening in the partitioning plate, between the suction chamber 20, and distributing chamber 21.

The valve 49, being closed and the float 37, being down, suction induced by the engine gives a subatmospheric condition in the chamber 20, and the liquid seal chamber 36. Fuel is now drawn into the chamber 20, through the tube 33. As the fuel rises above the lower edge of the inverted cup 34, it will form a "liquid seal" separating the chamber 36, from the chamber 20. A continued rise of fuel will take place in both chambers, but the rate of rise will be greater in the chamber 20.

When the level of fuel in the chamber 36, rises to an extent to immerse the float 37, and give it sufficient buoyancy, the float will rise. The first movement of the float opens the relief 52, and a further movement opens

the valve 49. Thereupon, the contents of the upper chamber 20, will begin to drop to the distributing chamber 21, owing to the percolation of air from the chamber 21, to the chamber 20, as the difference in pressure of the chambers tends to equalize.

As soon as there is an increase of pressure in the chamber 20, there is a rise of level of fuel in the liquid seal chamber 36, which causes the float to rise to its highest position, bringing its stop 37^a, against the lower end of the fuel tube 33. The valve 49, is now fully opened and permits complete discharge of the chamber 20, into the chamber 21. The stop 37^a, closes the end 80 of the inlet tube 33, and prevents flow of fuel therethrough.

As the level of the fuel in the chamber 20, falls to the lower edge of the liquid seal chamber 36, there will be no dropping of the float 37, as it is still buoyant in the fuel contained and held within the chamber 36. This condition will maintain until the level has fallen sufficiently to admit air to the chamber 36, whereupon the relative pressures of the chamber 36, and the chamber 20, will equalize, and the chamber 36, will discharge its contents with great rapidity. Thereupon, the float 37, will drop, giving a "hammer-blow" effect for the closing of the valve 49.

The above described cycle of operation will continue so long as the distributing chamber 21, requires a charge of fuel, and suction in the upper chamber 20, is maintained by the operation of the engine.

The liquid seal chamber 36, is, in itself, a buoyant element; and through the tubular connections and bearings 35, 38, a certain amount of adhesion exists, so that the inverted cup in its upward movement (due to its buoyancy) tends to aid and make more effective the upward movements of the float.

It will be apparent from the above that a most certain operation is insured for controlling the conditions of suction, fuel levels in the suction chamber, and the discharging of such fuel into the distributing chamber.

The simplicity of the device, with its features of efficiency, makes it possible to produce a structure having unusually perfect action and merit at a minimum expenditure of labor and costs.

It is most accessible, inasmuch as the main casing need not be disturbed when all of the operating parts are removed. A loosening of the upper strap 22, and the fuel and suction connections 26, and 27, permits removal of the operating chamber as a unit with the entire operating mechanism. The valve may thus be inspected and adjusted without removing the supporting and partitioning plate 19. A removal of the partitioning plate 19, carries with it the entire valve mechanism and operating float. The in-

verted cup 34, may then be removed with great facility.

The details of the pump and other connections, and the form of the pump may, of course, be varied to suit the exigencies of any particular case. The advantages of utilizing the circulatory system for the lubricating fuel, as a means for producing suction in the chamber 20, is apparent. Whether used as the only means of producing said suction or used co-operatively with the suction of the engine, is a matter of selection.

It is not imperative that an injector such as described be used to effect the necessary suction. In fact, very satisfactory results have been attained, in the practice of the invention, by simply leading the suction pipe line directly into the oil circulating system, at the suction side of the pump.

In Fig. 6 of the drawings, there is illustrated the same arrangement of casing members, chambers, float and controlling valve, between the suction or operating chamber and the distributing chamber, as heretofore described in conjunction with Fig. 3.

The connecting block for the fuel inlet and suction connection, while of the same form heretofore described, is so arranged as to provide a convenient means of valve control for the fuel inlet.

In Fig. 6, the outer casing A, has a telescopic engagement with the casing B, and the bottom plate C, divides the structure into a suction or operating chamber D, and a distributing chamber E, the same as in Fig. 3.

A valve F, constructed, operating, and having connecting parts, the same as described in Fig. 3, controls the valve opening G, between the chambers D, and E. This valve is controlled by a float H, extending into the liquid seal chamber I, and is connected with the valve and appurtenant parts through a lever J.

The casing i of the liquid seal chamber I, slides upon a guide k, secured to the head of the casing B, and has a bearing tube j, which forms a guide and bearing for the float H.

The connecting block K, is of substantially the same form as that of Fig. 3, but is arranged at one side of the center of the casing B. It is provided with a fuel inlet L, and a suction connection, which through an opening l, communicates with the suction chamber D. Internally of the connecting block K, there is a valve seat m, having a controlling valve M, and projecting within the chamber D, below the valve seat m, and its valve M, there is a tubular strainer O. This strainer serves to strain the in-flowing fuel, and its lower end o, is perforated to provide a guide for the valve stem n, of the valve M. A screw plug N, is arranged in line with the valve M, giving access to said valve and serving as a priming plug.

The valve stem n, is of sufficient length to rest upon the valve lever J, and the parts are so arranged that the valve M, is raised from its seat when the valve F, is closed and the float H, is down.

When the float H, rises, opening the valve F, the valve M, drops to its seat and cuts off further flow of fuel to the suction chamber D.

Inasmuch as the valve M, operates in unison with the valve F, it is apparent that there is no liability of "flooding".

If the engine suction is employed, either in combination with the oil pump or separately, unusual advantages are attained by making the terminal connection as indicated at the throttling point and in a form which extends to opposite sides of the throttle valve when the latter is in closed or nearly closed position.

What I claim as my invention and desire to secure by Letters Patent is:

1. The combination with an internal combustion engine having a carburetor and a lubricating system; of means for feeding fuel to said engine comprising a suction chamber and a distributing chamber, a valve and valve mechanism for controlling the flow of fuel from the suction chamber to the distributing chamber, a fuel tank, a connection from the fuel tank to the suction chamber, a connection from the distributing chamber to the carburetor, a lubricating system, a pump driving oil through said system, an injector arranged in the oil circulating system, and a connection from said injector to the suction chamber, whereby the circulation of oil creates a sub-atmospheric condition in said chamber.

2. In combination with a liquid feeding apparatus for gas engines operated by suction induced by the engine and having a suction chamber, an oil pump for the engine, connections for said pump through which the lubricant of the engine is circulated, an injector arranged in the connections of the lubricating system, and a suction connection from said injector to the liquid feeding apparatus, whereby a circulation of lubricant through the lubricating system and injector induces a suction in the liquid feeding apparatus.

3. The combination with an internal combustion engine having a carburetor, connections therefrom to the intake side of the engine, a throttle for the carburetor, a lubricating system, a pump for circulating lubricant through said system; of a fuel feeding device, utilizing suction to raise fuel for distribution to the carburetor, means for inducing suction in said fuel feeding device consisting of a connection therefrom terminating adjacent to the throttle valve whereby the vacuum in the intake connection of the engine induces a suction for the fuel

- feeding device, and a connection from said fuel feeding device to the pump of the lubricating system, whereby the movement of lubricant through said system induces a suction for the fuel feeding device, and means for controlling both of the suction connections.
4. The combination with an internal combustion engine having a lubricating system comprising a pump and pipe connections through which said pump circulates lubricant for the engine; of a fuel feeding device for the engine employing suction for moving fuel for distribution to said engine, an injector co-operatively related with said pump and its connections, and a connection from said injector to the fuel feeding device through which suction induced by the passage of lubricant through the injector induces the necessary suction for the fuel feed device.
5. The combination with an internal combustion engine having a pump driven by the engine for circulating liquid, and pipe connections for said pump through which liquid is circulated; of a fuel feeding device employing suction for moving fuel for distribution to the engine, a suction connection from said fuel feeding device to the intake side of the circulating pump, whereby the pump in circulating liquid through its pipe connections induces a suction in the suction connection for the fuel feed device during the circulation of liquid, and an injector arranged in the pipe connections in which the liquid is circulated, located between the pump and the fuel feeding device.
6. In a device of the character described, a suction chamber, a distributing chamber, a valve opening, a valve controlling communication between said chambers, a float for controlling said valve, a fuel inlet for the suction chamber, and a valve controlling said inlet, said valve having a stem projecting into the path of movement of the float controlled valve and actuated thereby.
7. In a device of the character described having a suction chamber and a valve mechanism for controlling the action of the suction chamber; a sectional float for controlling the valve mechanism, an inverted cup encircling said float, and a cup-like baffle seated between the sections of the float and extending upward toward the lower end of the inverted cup.
8. In a device of the character described, a suction chamber, a distributing chamber, a valve-opening between said chambers, a valve controlling said opening, a float for controlling said valve, a fuel inlet for the suction chamber, and a valve controlling said inlet, said fuel inlet valve actuated by a movement of the float and co-related in its movements, with the movements of the valve, controlling the valve opening between the chambers.
9. In a device of the character described, a suction chamber, a distributing chamber, a valve-opening, and a valve controlling communication between said chambers, a float for controlling said valve, a fuel inlet for the suction chamber, a valve controlling said inlet and closing in the direction of flow of fuel to the suction chamber, and connections between said valve and the float-controlled valve whereby the former is opened upon a closing movement of the latter.
10. In a device of the character described, a suction chamber, a distributing chamber, a valve-opening, and a valve controlling communication between said chambers, a float for controlling said valve, a fuel inlet for the suction chamber, a screen extending therefrom, a valve controlling the fuel inlet, said valve having a stem projecting through the screen, and connections between the float and stem for actuating the fuel inlet valve.
11. The combination with an internal combustion engine, of a force feed lubricating system therefor, a fuel feed system, and means operated by the movements of the liquid in the lubricating system and connected with the fuel feed system, and arranged to control the operation of the latter, whereby when the lubricant fails to circulate, the feed of the fuel is automatically interrupted.
12. In a device of the character described, a suction chamber, a valve mechanism and valves controlling said suction chamber and controlling the flow of liquid thereto and therefrom, a float mechanism controlling said valve mechanism and valves, a fuel inlet for the suction chamber, a valve controlling said inlet, said valve closing in the direction of flow of fuel to the suction chamber, and means for automatically opening said valve.
13. In a device of the character described, a suction chamber, means for controlling the action of said suction chamber with respect to a liquid passing therethrough, a fuel inlet for said suction chamber, a valve controlling said fuel inlet and closing in the direction of flow of fuel to the suction chamber, and means for opening said valve at a predetermined level of fuel in the suction chamber.
14. In a device of the character described, a suction chamber, a fuel inlet for said chamber, a valve automatically closing under the pressure of flow of fuel to the chamber, and means operated by the change of level of fuel in said chamber for opening said valve.

JOSEPH C. COULOMBE.
